UNITED STATES PATENT OFFICE.

HAROLD R. SCHUTZ, OF TOLEDO, OHIO, ASSIGNOR TO THE EDWARD FORD PLATE GLASS COMPANY, OF ROSSFORD, OHIO, A CORPORATION OF OHIO.

CASTING TABLE.

Application filed September 15, 1926. Serial No. 135,528.

This invention relates to casting tables of the type commonly used in plants for manufacturing sheet or plate glass and adapted to be propelled along rails and beneath a set of rolls for flattening glass thereon in sheet or plate form. In some cases the table is stationary and the flattening roll or rolls moved thereon.

An object of the invention is the provision in a table of the character described of a base or truck frame and a top or table portion with the latter mounted on the former in a manner to allow for free contracting and expanding movements responsive to temperature changes without cracking, warping or disfiguring the top and also to permit an easy and rapid replacement of the top portion as occasion may require.

A further object of the invention is the provision of a sectional top portion in a table of the character described, whereby any section, should it become damaged, may be easily and quickly replaced. Further objects and advantages of the invention will be apparent from the following detailed description.

While the invention in its broader aspect is capable of embodiment in numerous forms, one embodiment thereof is illustrated in the accompanying drawing, in which,—

Figure 1 is a plan view of a casting table embodying the invention with parts of the top portion or table proper broken away. Fig. 2 is a side elevation thereof with a portion broken away. Fig. 3 is a cross-section on the line 3—3 in Fig. 2, and Figs. 4 and 5 are enlarged fragmentary sections on the lines 4—4 and 5—5, respectively, in Fig. 1.

The casting table embodying the invention comprises a base or truck frame portion 1 and a removable top portion 2, which latter forms the casting surface of the table. The truck frame 1 is carried by a plurality of wheels 3 to adapt it to travel on a guiding track and is preferably of skeleton form to facilitate cooling, and in its present embodiment is composed of four rectangular sections secured in respective end and side abutting relation by bolts 4.

The top 2 is intended to cover the truck frame top, being substantially coextensive in length and width therewith, and is separably attached to the frame by a center dowel pin 5 and dowel pin 7 disposed between the center pin and the ends of the

table. The dowel pin 5 fits snugly in all directions in a central socket 6 in the underside of the table top, so as to hold the engaged portion of the table against relative lateral movements in any direction, and each end pin 7 projects into a registering socket 8 in the underside of the table top. The sockets 8 are elongated lengthwise of the table, so that the pins 7 fit snugly therein crosswise of the table and have clearance lengthwise thereof to allow for expansion and contraction of the respective end portions of the table due to temperature changes and other causes. It is thus apparent that the table top is held firmly to the underframe at its central point due to the fitting in all directions of the pin 5 in the table socket 6 and that the portions of the top at both ends of the center dowel pin are free to expand and contract in all directions from the center without distorting the underframe in any way due to the clearance provided between the end dowel pins 7 and their sockets 8 lengthwise of the table and the snugly fitting of the same crosswise of the table. This construction also facilitates the replacement of the table top, should the same become damaged or unduly worn, as it can be quickly lifted from the frame and a new one substituted therefor.

It is preferable in practice, although not necessary, to make up the table top 2 in a plurality of sections 10 which are held together by bolts or tie rods 11 extending through all of the sections lengthwise of the table. The sections 10 in the present instance are co-extensive in length with the width of the table and have their side edges machined and forming close abutting joints and also provided with keys 12 fitting in registering recesses in the abutting sides of the adjoining sections. These keys preserve the vertical alignment between the various sections and keep the upper surface of the top portion true.

The sections of the top portion 2 are preferably formed with a thin top wall and with supporting flanges or webs 13 extending downward marginally and crosswise thereof and adapted to rest on the truck frame.

It is apparent that should any section or portion of the table top become broken or disfigured in use or while handling, the section or sections including the same may be quickly removed and new ones substituted

therefor, thereby obviating the necessity of replacing the entire table top in the event of damage or injury to only a portion thereof.

I wish it understood that my invention is

5 not limited to any specific construction, arrangement or form of the parts, as it is capable of numerous modifications and changes without departing from the spirit of the claims.

10 Having thus described my invention, what I claim as new and desire to secure by Letters Patent is:

1. A casting table comprising an under-frame and a top portion removably mounted thereon, the two having a single anchoring point of connection which prevents relative movements thereof in any direction in a lateral plane at such point and having connection in spaced relation to said point longitudinally of the table which permits the adjacent portions of the under-frame and top to have relative movements lengthwise of the table and prevents relative movements thereof transversely of the table.

25 2. A casting table comprising an under-frame and a top portion having a plurality of interengaging connections, with a part of said connections preventing relative movements of the underframe and top in any direction in a lateral plane and with a part thereof permitting such movements in one line and preventing the same in any other line.

3. A casting table comprising an under-frame and a top portion having a plurality of interengaging connections, with a part of said connections preventing relative move-

ments of the underframe and top lengthwise of the table, and a part permitting such relative movements lengthwise of the table and 40 preventing the same in any other direction.

4. A casting table comprising an under-frame and a top portion, the two having connection at one point to prevent relative movements thereof in any direction in a lateral plane, and having connection which permits relative movements lengthwise of the table of the portions thereof interposed between said first point of connection and an end of the table and prevents relative transverse movements thereof.

5. A casting table comprising an under-frame and a top portion mounted thereon, the two having connection at their central portions to prevent relative lateral movements thereof and having connection between the central portion and their ends to permit relative longitudinal contracting and expanding movements thereof and to prevent relative lateral movements thereof.

6. A casting table comprising a base frame, a table top removable mounted on the base frame, a dowel pin connection between the central portions of the base frame and top to prevent relative movements thereof in any direction in a lateral plane, and connection between the base frame and top intermediate said central connection and each end thereof to permit relative movements of the frame and top longitudinally thereof and to prevent relative lateral movements thereof.

In testimony whereof I have hereunto signed my name to this specification.

HAROLD R. SCHUTZ.
